UNITED STATES PATENT OFFICE

GEORGE D. FULL, OF WINNETKA, ILLINOIS, ASSIGNOR TO DUDLEY LOCK CORPORATION,
OF CHICAGO, ILLINOIS, A CORPORATION OF ILLINOIS

LOCK

Application filed September 14, 1925, Serial No. 56,273. Renewed April 30, 1931.

My invention relates to locks and more particularly to permutation or keyless locks whereby a series of tumblers having a predetermined setting are adapted for manual operation to release the locking shackle from closed position, the invention relating to certain peculiarities of the construction, novel arrangement and combination of the various parts thereof as will be hereinafter more fully set forth and specifically claimed.

The principal object of my invention is to provide a lock of the above mentioned general character, whereby the usual number of tumblers or operating elements are fitted into a lock casing and by means of the usual spacers and pins are adapted to be brought into a predetermined position by a manually operable dial on the exterior of the casing, to the end that a proper registration of the tumbler slots will permit a locking pawl to be withdrawn from engagement with the shackle, said locking pawl being of a novel form to provide added strength to the lock when engaging the shackle.

Another object of my invention is to provide the lock of such construction that a plurality of tumblers may be associated in a lock casing with a master tumbler, which is grooved or serrated about its periphery, so as to hold the locking pawl out of contact with the other tumblers, thereby preventing an unauthorized person from ascertaining the combination by feeling each time a tumbler slot is brought into proper registration.

A further object is to provide a structure which is simple and inexpensive in construction, strong, durable and effective in retaining its shackle securely held in locked position.

In the accompanying drawings which illustrate a convenient embodiment of my invention:

Figure 1 is a front elevation of a permutation lock embodying my invention;

Fig. 2 is a similar view, but with the cover and master tumbler removed to illustrate the manner in which the locking pawl engages the shackle in reinforced relation;

Fig. 3 is a similar view illustrating the locking pawl released from the shackle;

Fig. 4 illustrates the shackle moved to unlocked position, while its open position is shown in dotted lines;

Fig. 5 is a perspective view of the various parts of the lock including the tumbler mechanism, to illustrate the relative relation of these parts; and

Fig. 6 is a section taken on line 6—6 of Fig. 2.

In the drawings wherein I have illustrated a preferred embodiment of my invention, the lock comprises the usual lock casing 2 having a pair of openings near the upper end to receive the locking shackle 3. Opening 4 may be seen in Fig. 5 and it is through this opening that the free end 5 of shackle 3 may be inserted and held locked within casing 2 by means of a locking pawl 6.

The opposite end of shackle 3 is inserted through an opening 7. At this end of shackle 3, a collar 8 is fixed to serve as a stop so as to prevent the shackle from being entirely withdrawn from the lock casing, said collar serving to abut against an apertured lug 9 struck up from a holding plate 10, inserted in the casing 2 against its back wall 11, as shown in the sectional view illustrated in Fig. 6. It will be apparent that when the free end 5 of shackle 3 is released by locking pawl 6 this shackle may be pulled outwardly a limited distance from casing 2 so as to free the end 5 and allow the shackle to freely swing about the other end thereof, its entire displacement from the lock casing being prevented by collar 8 abutting against the apertured lug 9.

A tumbler mechanism containing the usual number of tumblers and spacers may be provided in the present instance as the means for releasing the locking pawl 6 from engagement with the shackle 3. As the present lock is of the permutation or keyless type, I contemplate providing a dial 12 as the front face for the lock casing 2. A knob 13 having a pointer 14 fixed thereto may be rotatably mounted in the center of dial 12. The inner end of knob 13 may be apertured as indicated at 15 so as to fit over the free end of the pin 16 fixed in the plate 10. This pin may be riveted, as indicated at 17, centrally in plate 10 and in axial alignment with the knob 13.

Pin 16 serves to carry a plurality of tumblers 20, as indicated in Fig. 5, which are adapted to be spaced by a plurality of spacing members 21, these members having a portion 22 provided with openings 23 permitting the spacing members 21 to be carried upon a pair of pins 24. These pins 24 are also riveted in the holding plate 10. Tumblers 20 are centrally apertured at 24' to permit the pin 16 to pass centrally therethrough and are each furnished with a pin 25. These pins 25 function to interlock and cause the tumblers to bring peripheral slots 26 into register with each other. It will be observed in Fig. 5 that a master or top tumbler 27 is also provided, this latter tumbler being riveted or fixed to the inner end of knob 13, that is to say, the master tumbler is adapted to rotate in fixed relation with the knob 13 so that upon proper manipulation of the knob the master tumbler will first interlock with the adjacent tumbler and then through this adjacent tumbler with the last tumbler, whereby the slots 26 and the cut-away portion 28 in the tumbler 27 will register or align with each other to permit locking pawl 6 to be disengaged from the shackle 3. A spring 40 may be provided to urge the spacers and tumblers together.

The construction of locking pawl 6 is an important feature of my invention in that its engagement with the shackle is strengthened when an unauthorized attempt is made to pull the free end 5 out of lock casing 2. It will be observed in Figs. 2 to 4, inclusive, that an acutely formed slot 30 is cut into the free end 5 of shackle 3 and in this slot a transverse engaging portion or shoulder 31 is adapted to engage. It will be observed that the slot 30 is extended downwardly at an acute angle with respect to a pulling force attempting to release the free end 5 of shackle 3. Shoulder 31 is formed at a similar angle. Locking pawl 6 is pivoted at 32 in the casing and is adapted to have one of its edges engaged against the free end 5 of shackle 3. Shoulder 31 is so formed that it will abut against the inner surface of the lock casing when engaging in slot 30. This provides a strong interlocking engagement between the pawl and shackle which is of particular advantage at a time when an attempt is made to force the shackle loose from the casing. The edge 33 of locking pawl 6 will at the same time bind against the lower edge of the free end of shackle 3 while the shoulder 31 engages in slot 30 at an acute angle in a direction opposite to that which the pulling force is being exerted.

In order to guard against a person determining when the slots 26 and 28 all come into alignment with each other, thereby feeling out the combination, this usually being accomplished by pressing the shackle downwardly so as to bring the locking pawl's engaging portion 35 into peripheral contact

with the tumblers, the master tumbler, 27, is made larger in diameter than the other tumblers, 20. I provide a plurality of serrations or teeth on the periphery of the master or top tumbler 27 and project these serrations or teeth slightly beyond the edge of the periphery of the other tumblers so as to normally have the engaging edge 35 of the locking pawl riding over these serrations or teeth. The serrations or teeth in the master tumbler are produced by forming the periphery thereof with a series of spaced false notches indicated at 27^a, whose bottoms are defined by a radius greater than the radius of the other tumblers. Thus an attempt to "feel out" the combination by ascertaining when the pawl-receiving notches, 26 and 28, align is precluded, since these false notches, 27^a, which themselves are adapted to receive the engaging edge, 35, of the locking pawl when the shackle is depressed in the manner mentioned, will always hold the pawl out of contactual engagement with the periphery of the other tumbler disks, 20. A leaf spring 37, as illustrated in Fig. 5, normally urges the shackle upwardly by engaging the end which passes through the apertured lug 9. This spring tends to hold the slot 30 in register with the engaging shoulder 31 of locking pawl 6 when the free end 5 of shackle 3 is inserted in opening 4 of lock casing 2. It will be observed that the inclined walls of slot 28 will cam the locking pawl upwardly out of engagement with the slots 26 when it is desired to again move the locking pawl 6 into engagement with the slot 30 of shackle 3. On the other hand, the locking pawl 6 is moved downwardly into engagement with these slots 26 and 28 by pressing the shackle 23 downwardly when the proper combination of the tumblers has been found. The dial 12 may be provided with any number of divisions, say, from zero to 40, inclusive, while the tumblers may be so arranged with reference to their pins 25 and slots 26 that any desired setting will serve to operate the lock. This is common in the construction of permutation locks and I deem it unnecessary to give a further explanation thereof.

Other embodiments and modifications of the details shown herein may be had without departing from the spirit and scope of my invention.

I claim:

1. In a permutation lock, a casing, locking means including a part movably mounted in the casing, tumbler mechanism for controlling the movement of said means including a series of superimposed tumbler disks each having a peripheral notch adapted to be registered with said movable part to permit movement thereof in approximately radial direction, and an exteriorly accessible member adapted for adjusting said tumbler disks

in registered relation; one of said tumbler disks being larger in diameter than the others, and having its periphery formed with a plurality of circumferentially spaced radially extending shoulders of less depth than the shoulders forming said peripheral notch, and having its entire periphery except a portion of said notch lying outwardly beyond the peripheries of said other tumblers, whereby said shouldered tumbler disk prevents contact of said movable part with the other disks unless its peripheral notch is registered with said part and said disk itself is held against rotation by encounter of said movable part with any one of its said shoulders.

2. In a permutation lock, a casing, locking means including a part movably mounted in the casing, tumbler mechanism for controlling the movement of said means including a series of super-imposed tumbler disks each having a peripheral notch adapted to be registered with said movable part to permit movement thereof in approximately radial direction relative to the disks, and an exteriorly accessible member adapted for adjusting said tumbler disks in registered relation; one of said tumbler disks being larger in diameter than the others, and having its periphery formed with a plurality of circumferentially spaced false notches of less depth than said first mentioned notches, the bottoms of said false notches being located at a distance from the center of said tumbler greater than the radius of the other tumblers, whereby contact of said movable part with the other tumblers is prevented when said part is entered in one of the false notches.

3. In a permutation lock, a casing, locking means including a part movably mounted in the casing, tumbler mechanism for controlling the movement of said means including a series of super-imposed tumbler disks comprising a master tumbler and an exteriorly accessible member connected thereto for rotating it, and a lost motion connection between each tumbler and the next of the series, whereby rotation may be imparted from the master tumbler to the other disks for adjusting them in registered relation; each of said tumbler disks having a peripheral notch adapted to be registered with said part to permit entry of the latter therein, and said master tumbler having its entire periphery except the aforesaid notch lying outwardly beyond the peripheries of said other tumblers, whereby said master tumbler serves to block inward movement of the movable part to prevent contact thereof with the other tumblers during their adjustment by rotation of the master tumbler.

4. In the combination defined in claim 3, said master tumbler having its periphery provided with a plurality of spaced false notches of less depth than its first mentioned notch, the bottoms of said false notches be-

ing located at a distance from the center of said tumbler greater than the radius of the other tumblers, whereby contact of said movable part with the other tumblers is prevented when said part is entered in one of the 70 false notches.

GEORGE D. FULL.
